DESIGN FOR A JAYHAWK PAPERWEIGHT

Walter A. McClain, Lawrence, Kans.

Application October 17, 1938, Serial No. 80,519

Term of patent 14 years

To all whom it may concern:

Be it known that I, Walter A. McClain, a citizen of the United States, residing at Lawrence, in the county of Douglas and State of Kansas, have invented a new, original, and ornamental Design for a Jayhawk Paper Weight, of which the following is a specification, reference being had to the accompanying drawing, forming part thereof.

Figure 1 is a side perspective view of a jayhawk paper weight; and

Figure 2 is a rear elevational view thereof, showing my new design.

I claim:

The ornamental design for a jayhawk paper-weight, as shown.

WALTER A. McCLAIN.
